UNITED STATES PATENT OFFICE.

LEWIS G. MCCLINTOCK, OF PITTSBURGH, PENNSYLVANIA, ASSIGNOR TO PITTSBURGH TRANSFORMER COMPANY, A CORPORATION OF PENNSYLVANIA.

TANK FOR TRANSFORMERS AND THE LIKE.

Application filed September 26, 1923. Serial No. 664,948.

To all whom it may concern:

Be it known that I, LEWIS G. MCCLINTOCK, a citizen of the United States, residing at Pittsburgh, in the county of Allegheny and State of Pennsylvania, have invented certain new and useful Improvements in Tanks for Transformers and the like, of which the following is a specification.

This invention relates to tanks for transformers and the like, and particularly to a tank having pipe connections to its interior for instance for the circulation of a cooling fluid through cooling coils within the tank.

The body of the tank is often formed of sheet steel which is corrugated to give a large cooling surface and with such a tank it is difficult to provide for the passage of pipes to the interior. The joints between the tank and the pipes are complicated in form, due to the corrugated shape of the metal, and are weak and likely to fail under the strains of service.

The object of this invention is to overcome these difficulties and provide a tank in which the pipe connections to the interior of the tank will be strong and reliable in service and inexpensive in cost.

In the accompanying drawings illustrating the invention,

Fig. 1 is a perspective view of a portion of a transformer tank showing the pipe connections thereto.

Fig. 2 is a vertical sectional view of the same taken on line 2, 2 of Fig. 1, and

Fig. 3 is an enlarged view of the pipe connections shown in Fig. 2.

In the embodiment of the invention shown in the drawings, a transformer tank T has its body portion provided with corrugations 5 formed by bending of the sheet metal of the body portion. The upper ends 6 of the corrugations are inclined downwardly and bent over in arched form to a central welded portion 7 forming the crest of each corrugation. The ends of the inner bends of the corrugations are hammered outward in inclined form as indicated at 8 so as to form an inclined ridge extending around the end of the body portion of the transformer and just within the top of this inclined surface is fitted the vertical flange 9 of the top ring 10 formed by a curved angle iron having its horizontal flange 11 extending outwardly to support the transformer tank

cover. This tank construction is substantially as described in a co-pending application of R. V. Bingay, Serial No. 386,115.

In the tank of this invention some of the corrugations such as those indicated at 15 are not carried all the way up to the top of the tank and the space left by discontinuing these corrugations is occupied by a plate P carrying the pipe connections leading to the interior of the tank. The corrugations 5 on each side of the corrugations 15 are cut along the lines 16 to receive the side edges of the plate P and to be welded thereto, and the top edge of the plate P is positioned and formed to be continuous with the end ridge formed by the bent over ends 8 of the corrugations. This upper edge 17 of the plate P is welded at 18 to the vertical flange 9 of the end ring 10 in the same manner as the surfaces 8 are welded to said ring. Similarly, the plate P is welded to the adjacent corrugations 5 on each side along the lines 16.

The shortened corrugations 15 are formed at their upper ends by arching over the metal to meet in a central weld 20 similar to the ends of the corrugations 5; and the inner ends of these corrugations 15 are bent outward as indicated at 21 to form inclined portions similar to the portions 8 having a continuous ridge 22 extending between the opposite corrugations 5 on each side. The lower edge of the plate P just fits within this ridge 22 and is welded thereto as indicated at 23. The plate P is therefore fitted and welded into the space formed by the shortening of the corrugations 15.

Carried by the plate P are the stuffing boxes B passing the pipes 25 to the interior of the tank. Each stuffing box comprises an annular body portion 26 of machined steel having a pipe aperture 27 and a stuffing recess 28 in which the packing 29 is compressed by the packing ring 30 pressed inward by the bolts 31. The body portion 26 of the stuffing box is fitted within a correspondingly shaped recess in the plate P, the adjacent edge 33 of the plate being bent or turned outward as indicated. On the interior the plate P is welded to the body 26 by an electric arc weld 34 extending into the annular groove between the body 26 and the plate. On the outside the plate P is welded to the body portion 26 by an acetylene weld 35 in the annular groove 110

formed between the edge of the plate P and the body 26. The stuffing box B is thus welded in place in the plate P which in turn is welded in place as a portion of the 5 body of the tank T.

In the tank of this invention the tank body is relieved of the direct strains of the pipe connections, the plate P intervening between the tank body and these connections. This plate P may be of any desired thickness, and having an extended connection with the sheet metal of the transformer tank, it is held strongly and securely in place and in turn carries the pipe connections to 10 which it is bound by strong welds on the inside and the outside of the tank. Any strains coming on the pipe connections are transmitted first to the plate P which has such an extended bond with the metal of the 15 tank body and the top ring 10 above, that the strains transmitted to the tank are widely distributed and correspondingly reduced in intensity. The construction is 20 simple and economical, merely requiring the tank corrugations 15 of the tank to be made shorter than the others so as to leave the space into which is fitted the plate P carrying the pipe connections so that the latter is 25 flush with the inside of the tank. The tank 30 is of sheet steel, the plate P of plate steel and the body 26 of the stuffing box B is of machined steel so that the intermediate 35 welds are easily made and strong bonds provided which are secure against failure or leakage.

I claim:—

1. The combination in a tank for transformers and the like, of a sheet steel tank body formed with corrugations having a 40 portion cut away, a plate steel member fitted in said cut away portion and welded to the adjacent edges of the tank body, and a pipe connection carried by said plate.
2. The combination in a tank for 45 transformers and the like, of a tank body having corrugations with one or more of said corrugations shorter than the others so as to leave a space at the end of the tank body, a plate member fitted in said space and welded

at its edges to the body of the tank, and a 50 pipe connection welded to said plate.

3. The combination in a tank for 55 transformers and the like, of a tank body having corrugations closed at their ends and having inner portions forming an end ridge of the tank body, one or more of said corrugations being shorter than the others so as to leave a space at the end of the tank body, an end member fastened to said ridge and spanning said space, a plate member fitted 60 in said space and welded at its edges to the body of the tank and said end member, and a pipe connection welded to said plate.

4. The combination in a tank for 65 transformers and the like, of a sheet steel tank body formed with corrugations having a portion cut away, a plate steel member fitted in said cut away portion and welded to the adjacent edges of the tank body, and a pipe connection carried by said plate, the edges 70 of the plate being turned over adjacent said pipe connection and welded thereto at both the outside and inside.

5. The combination in a tank for 75 transformers and the like, of a tank body with corrugations formed at their ends into a ridge, an end member extending around the tank and welded to said ridge, one or more of said corrugations being shortened, a plate member having one of its edges welded to the 80 end of said shortened corrugations and its opposite edge welded to said end member, and a pipe connection carried by said plate member.

6. The combination in a tank for 85 transformers and the like, of a tank body with corrugations formed at their ends into a ridge, an end member extending around the tank and welded to said ridge, one or more of said corrugations being shortened and 90 formed at their end into a ridge extending between the unshortened corrugations on each side, a plate member having one of its edges welded to the end of said shortened corrugations and its opposite edge welded 95 to said end member, and a pipe connection carried by said plate member.

LEWIS G. McCLINTOCK.
